UNITED STATES PATENT OFFICE.

JOHN R. SEARIGHT, OF DETROIT, MICHIGAN.

PENCIL-SHARPENER.

1,108,478.

Specification of Letters Patent.

Patented Aug. 25, 1914.

Application filed December 28, 1912. Serial No. 733,983.

To all whom it may concern:

Be it known that I, JOHN R. SEARIGHT, a citizen of the United States of America, residing at Detroit, in the county of Wayne 5 and State of Michigan, have invented certain new and useful Improvements in Pencil-Sharpener, of which the following is a specification, reference being had therein to the accompanying drawings.

10 My invention relates to pencil sharpeners and more particularly to that type of sharpener which is provided with a chamber or receptacle for receiving the cuttings.

The invention resides in the provision of 15 a simple and efficient device that may be easily and cheaply manufactured; in a construction in which the knife may be readily adjusted or removed; and in the novel formation of a seat for the knife, whereby 20 clogging of the latter is prevented.

In the drawings, —Figure 1 is a perspective view of my improved pencil sharpener; Figs. 2 and 3 are similar views, respectively, 25 of the body portions and the cover; and Figs. 4 and 5 are sections on the lines $x-x$ and $y-y$ of Fig. 1.

A designates the case or receptacle which is composed of a body portion B having a removable top wall or cover C and a knife 30 or blade D. The latter is carried by the cover, which is provided with a seat having a longitudinal slot E therein over which the blade is arranged, and provided with a comparatively flat portion F in rear of the 35 slot to which the blade is secured as by means of screws G. These screws pass through elongated apertures H adjacent opposite ends of the blade and engage threaded openings I in the seat. Thus, by loosening 40 the screws the blade may be adjusted within the limits of the elongated apertures H. In advance of the flat portion is a raised section J constructed to form at opposite ends of the slot inclines K L, the apices M 45 of which—as will be apparent upon reference to Fig. 3—are slightly in rear of the front edge N of the slot. This arrangement is very desirable since it provides in all positions of adjustment a space between the 50 cutting edge O of the blade and the front edge of the slot, thereby preventing clogging of the blade.

In order to reduce the cost of manufacture to a minimum, the body portion and cover 55 are both shaped so as to be stamped from a flat piece of metal. As shown, the body por-

tion comprises a substantially rectangular open-top member having the free edges of the sides terminating in slightly out-turned flanges Q, while the cover has down-turned flanges R which have a sliding engagement with the outwardly extending flanges of the body and which are bent inward sufficiently to prevent disengagement of the cover except by a sliding movement. At one end of 60 the cover the down-turned flange is discontinued so as to allow the engagement or disengagement of the body and cover.

By the arrangement of parts heretofore described it will be noted that the blade extends longitudinally of the case or receptacle and, therefore, in sharpening the pencil the device may be used in the same manner as a knife. Also the blade extends for a portion only of the length of the case, 75 which leaves a space on the cover that may be utilized for advertising matter or the like.

What I claim as my invention is:—

1. A pencil sharpener, comprising an 80 elongated receptacle having a wall thereof provided with a seat slotted longitudinally of the receptacle and extending for a portion only of the length of the receptacle, the remaining portion of the receptacle 85 forming a hand-grip, and a knife engaging said seat having its cutting edge extending longitudinally of the receptacle and positioned in operative relation to said slot.

2. A pencil sharpener, comprising a 90 body portion stamped from a piece of metal and having out-turned flanges and a cover having in-turned flanges slidably engageable by a relative longitudinal movement of the cover and body, said flanges prevent- 95 ing disengagement of the cover from the body by a relative lateral movement, said cover being provided with a seat slotted longitudinally of the cover, and a knife engaging said seat having its cutting edge ex- 100 tending longitudinally of the cover and positioned in operative relation to said slot.

3. A pencil sharpener, comprising a com- 105 paratively narrow elongated receptacle having a wall thereof provided with a seat slotted longitudinally of the receptacle and extending for a portion only of the length of the receptacle, the remaining portion of the receptacle forming a hand-grip, said seat having inclines arranged at opposite 110 ends of said slot with the apices of the inclines slightly in rear of said slot, a blade

provided with elongated apertures and having the cutting edge thereof extending longitudinally of the receptacle, said blade engaging said seat and having its cutting edge positioned by said inclines in operative relation to the front edge of said slot, and securing screws passing through the elongated apertures and engaging the receptacle, said receptacle including a cover.

10 4. A pencil sharpener, comprising a comparatively narrow elongated receptacle composed of a body portion stamped from a single piece of metal and a cover formed from a stamping, said cover and body portion being provided with interlocking flanges engageable by a relative longitudi-

nal sliding movement of the body and cover, said cover being longitudinally slotted for a portion only of the length of the cover, and a knife arranged in operative relation to 20 said slot and extending longitudinally of the cover, said receptacle having a portion of sufficient length beyond one end of the slot to form a hand-grip, for the purpose described.

25 In testimony whereof I affix my signature in presence of two witnesses.

JOHN R. SEARIGHT.
